ATTORNEY

UNITED STATES PATENT OFFICE.

JOHN E. YINGLING, OF TOPEKA, KANSAS.

HEADLIGHT LAMP.

Application filed March 10, 1924. Serial No. 698,082.

To all whom it may concern:

Be it known that I, JOHN E. YINGLING, a citizen of the United States, residing at Topeka, in the county of Shawnee and State of Kansas, have invented certain new and useful Improvements in Headlight Lamps; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to headlight lamps for motor vehicles and motor boats and the like and the primary object of the invention is to provide an improved deflecting mechanism for deflecting the rays of light below the vision of pedestrians and below the drivers of on-coming vehicles so the danger of blinding the pedestrians or drivers of on-coming vehicles by the glare of the lamps will be eliminated.

Prior to my invention, many devices have been provided for deflecting the rays of the lamp toward the ground and to prevent the light rays spilling in an upward direction, for example, prior to my invention hoods have been provided, either adjustable or fixed, arranged at the upper portion of the lamp, but in so far as I am aware, none of these deflecting mechanisms included means at the upper portion of the lamp for shutting off the light and shutters at the lower portion of the lamp for rendering the lower portion of the reflector ineffective so the hooded constructions were objectionable because they did not completely solve the problem, due to the fact that the light rays reflected from the lower portion of the reflector were drawn out and above the outer edge of the reflector hood at the upper portion of the lamp.

My invention eliminates the objections heretofore encountered and it consists in certain novel parts and combination of parts, all of which will be specifically described hereinafter, reference being had to the accompanying drawings, in which—

Fig. 1 is a longitudinal, sectional view through a lamp constructed in accordance with my invention.

Fig. 2 is a front view of the lamp, parts being shown in section.

Fig. 3 is a fragmentary perspective view

of the upper and lower shutter members and the shutter actuator.

Fig. 4 is a sectional view through the shutter actuator, and

Fig. 5 is a detail elevational view of an actuator disk.

The lamp 1 is provided with a reflector 2 of usual construction and there is a light source consisting of a bulb 3 appropriately located in the lamp. The rim 4 is provided with a segmental slot 5 to receive pivoted shutters 6, 7 and 8 which constitute a reflecting hood mounted upon the pivot bolts 9 and 10. The innermost segment 6 has a depending flange 12 which closes the front of the slot 5 when the hood is extended as shown in Fig. 1. The pivot 9 carries an actuating sleeve 13 having stepped recesses 14 and 15. The stepped recess 15 is provided with slots of different arc lengths to progressively engage the edges of shutters 16, 17 and 18 mounted on the pivot 9 and adapted to be moved over the bottom portion 19 of the reflector 2 as shown in Fig. 1, at the same time that the hood is extended.

The recessed portion 14 is slotted in substantially the same manner as the portion 15 so that the segments 6, 7 and 8 are progressively picked up to extend them forward as shown in Fig. 1. The segment 16 is received in an end recess 20, in the end of the actuator 13, see Fig. 3, so that it moves with the actuating sleeve 13. The segments 17 and 18 however are picked up one after the other to extend them over the reflector and shut off the reflecting surface so that the rays of light from the light source 3 will not be directed upward. The segments are normally urged in either collapsed position or in extended position by a spring 21 which is anchored at 22 to the casing 1 and which is fastened on the disk or head 23 at 24. The disk or head 23 is in the form of a pulley with a groove 25 around which a cable 26 passes, the cable being operated from the front of the car or from a convenient point on the motor boat. When the spring connection 24 swings to one side of the vertical axis or to one side of dead center position in one direction, the shutters will be closed and when it swings to the other side of dead center position, the shutters will be extended. This will be clearly apparent by reference to Fig. 5.

Any well known mechanism may be used for operating the cable 26.

Since the angle of reflection is equal to

the angle of incidence, it will be apparent that when the deflectors are in the position shown in Fig. 1, the light rays will be directed downward only and no light rays can be directed in an upward and outward direction. It will also be apparent that when the deflectors are not in use the hood members will be received in the recess 5 while the bottom deflecting segments will be collapsed at the front of the lamp. When in this position the lamp will function as an ordinary lamp, but whenever it is desired to throw the lamp rays downward the actuator will be swung to cause the members 6, 7 and 8, 16, 17 and 18 to more or less approximate the arrangement shown in Fig. 1.

What I claim and desire to secure by Letters Patent is:

1. A head light lamp comprising a casing, a reflector and a light source, in combination with a movable hood consisting of a plurality of hinged segments at the upper portion of the lamp and a movable reflector covering means consisting of a plurality of hinged segments at the lower part of the reflector.
2. A head light lamp comprising a casing, a reflector and a light source, an extensible and contractable hood receivable in a groove in the casing and an extensible and contract-

able covering means for the lower part of the reflector.

3. A head light lamp comprising a casing, a reflector and a light source, an extensible and contractable hood receivable in a groove in the casing and an extensible and contractable covering means for the lower part of the reflector, and means for simultaneously actuating the hood and the covering means.

4. A head light lamp comprising a casing, a reflector and a light source, in combination with a plurality of semi-circular hood forming elements and a plurality of semi-circular reflector covering elements, the two sets of elements co-operating to close off the lower portion of the reflector and direct the light rays downwardly.

5. A head light lamp comprising a casing, a reflector and a light source, a hood comprising a plurality of segments pivotally secured to the casing, a reflector covering means comprising a plurality of pivoted segments and a shouldered actuator carried by the casing, and adapted to successively move the segments of the hood and the covering means and means for opposing the movements of the segments by the actuator.

In testimony whereof I affix my signature.

JOHN E. YINGLING.
